PORTABLE ELECTRIC JIG SAW

Marshall B. Johnson, Bel Air, Md., assignor to The Black
and Decker Manufacturing Company, Towson, Md., a
corporation of Maryland

Filed Apr. 21, 1961, Ser. No. 64,852

Term of patent 14 years

(Cl. D93—3)

FIG. 1

FIG. 2

FIG. 3

FIG. 4

FIG. 5

FIGURE 1 is a front perspective view of a portable electric jig saw;

FIGURE 2 is a side elevational view thereof;

FIGURE 3 is a front elevational view;

FIGURE 4 is a rear elevational view; and

FIGURE 5 is a top plan view.

The dominant features of my design reside in the portions shown in full lines.

I claim:

The ornamental design for a portable electric jig saw, as shown and described.
